UNITED STATES PATENT OFFICE

LEON LEBLANC, OF LA COUTURE BOUSSEY, FRANCE

SAXOPHONE

Application filed October 4, 1926, Serial No. 139,498, and in France May 28, 1926.

The present invention relates to new and useful improvements in the type of woodwind instruments having barrels sequentially pierced with holes spaced from one another to the musical extent of a half tone and it has more particular reference to saxophones and to the mechanisms used in that class of instruments for properly opening and closing the said holes.

The primary object of the invention is to provide a saxophone wherein, given its highest fundamental or normally emitted sound, the holes corresponding to all the fundamental sounds that it can emit will remain open and wherein moreover the number of open holes will be equal to the number of fundamental half tones that said saxophone will possibly emit.

A further object of the invention is to provide a saxophone embodying suitable mechanisms whereby the player will be at liberty to produce a sequence of tones by opening a single hole for every new tone so as to secure a sequence of tones and by each time lifting only one finger but a different one.

A still further object of the invention is to provide a saxophone embodying suitable mechanisms for performing the automatic actuation of the octave keys by means of one finger only to wit: the left ring finger.

Such being the principal objects of the invention—other objects will incidentally appear in the following description—it comprises the novel construction, arrangement and combination of parts that will now be exemplified in the following description, reference being had to the accompanying drawings wherein:—

Figure 1 is a diagrammatic developed view of the mechanism for producing the lowest C#.

Figure 2 is a similar view of the mechanism applicable to the normally open hole corresponding to the sound E#.

Figure 3 is a similar view of the mechanism for producing by means of such a saxophone provided with an open G# the sequence of whole tones: F#, G#, A#, C by lifting one finger only for producing each tone, also of the additional mechanisms increasing the

acoustic range of the saxophone for producing a top F# and top G.

Figure 4 is a similar view of the mechanism performing the automatic actuation of the octaves by means of one finger piece only corresponding to the thumb.

Like references apply to like parts throughout the several views.

As illustrated in Figure 1, when at rest the hole C# through which is emitted the bottom C# is open, the plate adapted to close said hole being connected to the rock shaft or hinge 2 by the pointed link 3. The rock shaft 2 is pivotally mounted between the studs 2a forming bearings and has welded thereon an arcuate arm 5 extending in the direction opposite to that of the link 3. A strong needle spring 2b located underneath the rock shaft 2 raises the plate 1 and lowers the arm 5 which thus presses upon the arm 18.

The cover 4 adapted to be depressed by the left little finger by means of an ordinary key (not shown), has welded thereto an arm 6 the enlarged end of which contracts with the plate 1 and actuates it when required. To the two ordinary finger pieces 7 and 8 controlling the sounds E# and C respectively there is added, according to the invention, a third finger piece 9 controlling the sound bottom C# by means of which the D hole bearing the reference B on the drawings may be closed.

Intermediate bearing studs 2b are pivotally arranged rock shafts 12 and 13 to which are welded the finger pieces 8 and 9. On the rock shaft 13 are secured the finger piece 9 and the pointed link 15 the end of which is fitted with the cover 10 by means of which may be closed or open the hole D through which is emitted the sound D; a needle spring 13b located underneath the rock shaft 13 raises the cover 10. On the finger piece 9 is secured a driving lug 14 having an extension underneath the finger piece 8.

The rock shaft 12 carries the finger piece 8 and a stop lug 11; on said lug is attached a needle spring 12b which lowers the finger pieces 8 and 9 as well as the cover 10 by overcoming the antagonism of its own spring 13b. The effect of the spring 12b is overcome by the

spring 2^c which lowers the arm 5 whereby the finger pieces 8 and 9 and the cover 10 are lifted. Such an action is performed through the medium of the levers 16 and 18 secured 5 to the rock shaft 17 which is pivotally mounted between the studs 17^c. The end of the arm 16 engages the underside of the finger piece 8 and, as the lever 18 is located underneath the arm 5, the depression of the cover 10 lowers the finger pieces 8 and 9 and the cover 10. Similarly the depression of the finger piece 8 lowers the finger piece 9 and the covers 10 and 1.

As illustrated in Figure 2 which represents 15 the mechanism used in connection with the open hole E_b (not shown) through which the sound E_b is emitted, the rock shaft of this mechanism is arranged in alignment with the main axis of the covers and finger pieces 20 actuated by the right hand. Intermediate the studs 25 and 26 is pivotally arranged the said rock shaft 27 which has welded thereto the stem of the cover 28 and the curved rod 29 whilst the other end of the rod 29 is welded 25 to the rock shaft 21 and carries an arm 22 which is thus indirectly connected with the rock shaft 27 and with the cover 28. The arm 22 is terminated by a small plate 23 adapted to receive the right middle finger. 30 The plate 23 is disposed above the cover 24 upon which it presses; a needle spring *i* located underneath the rock shaft 27 lifts the cover 28 and the said plate 23. When raising the middle finger of the right hand off the 35 finger piece 23, the latter is lifted by the spring *i* through the action of the rod 29, while the said spring acts at the same time on the cover 28 which produces the sound E_b.

The mechanism illustrated in Figure 3 40 makes it possible to produce the sequence of whole tones F_#, G_#, A_# and C by lifting one finger only for each tone. Said mechanism comprises eleven rock shafts 55 to 65 arranged between the studs 50 to 54. The rock shaft 55 carries the arm 66 and the rod 67; the arm 66 passes under the lug 68 welded upon the cover 69 and is actuated by said cover. Through the arm 67^a the rod 67 is connected to the rock shaft 57 so that the 45 rock shafts 55 and 57 are connected with the cover 71 welded on the pointed link 70 secured to the rock shaft 57; the tail portion of said link 70 passes under an extension of the rod 72. Said rod is welded on one end to the 50 rock shaft 58 and on the other end to the rock shaft 61. Upon this rock shaft is also welded the pointed link 73 of the rock shaft 74; the part 72^a of the rod 72 welded to the rock shaft 61 extends beyond said rock shaft so 55 as to abut upon a stem 75 and also secured to the pointed link 76 of the cover 77 at right angles to said link. The stem 75 passes under the pointed link 78 of the cover 90. Said pointed link 76 is welded to the rock shaft 64.

60 Owing to this connection, by depressing

the cover 69 the arm 66 is lowered and the rock shaft 55, the rod 67 and the rock shaft 57 are rocked whilst the cover 71 is depressed. The cover 69 is depressed by a rod acting on the cover to depress it, with such rod responding to the motion of an ordinary finger piece, such as indicated, for example, at the extreme right hand end of Figure 3. The tail portion 70 of the cover 71 lifts the rod 72 thereby oscillating the rock shaft 61 which lowers the cover 74 and the stem 75 thus depressing the cover 77. Therefore by depressing the cover 69, the covers 71, 74 and 77 are caused to close their respective holes.

70 The rock shaft 56 is co-operatively connected to the rock shaft 59 by the rod 78 which passes thereover and abuts on the pointed link 70 of the cover 71. On the rock shaft 56 is welded the pointed link 80 of the cover 81 whereas on the rock shaft 59 is welded the crank arm 82 of the plate 83. The arm 82 passes under the pointed link 84 but does not contact with it when it is lowered. The rod 85 is welded on the one end to the rock shaft 59 and on the other end to the rock shaft 65 upon which are secured the arms 49 and 48.

75 Owing to this connection, by depressing the plate 83, the cover 81 and the cover 71 are also depressed. The rod 78 then presses upon the pointed link 70; its tail portion is lifted and lifts the rod 72 whilst lowering the covers 74 and 77. The rod 85 thus swingingly lifted by the depression of the plate 83 lifts the arms 49 and 48 which in turn raise the arms 47 and 46 of the mechanism as illustrated in Figure 4.

80 The plate 86 secured on the crank arm 87 is located above the plate 74 but it is independent of said plate. However when depressing the plate 86 the plate 74 is also depressed. As moreover the arm 87 as well as the pointed link 84 of the cover 88 are welded upon the rock shaft 60, it follows that by depressing the plate 86 the cover 88 and the plate 74 and consequently the pointed link 73, the rod 75 and the cover 77 are also depressed.

85 The pointed link 78 of the cover 90 and the arm 92 are welded on the rock shaft 63; the pointed link 78 abuts on the rod 75. Furthermore, on the rock shaft 63 is secured the arm 92 which abuts on the arm 95 mounted on the rock shaft 91-93 oscillatingly carried between the bearing studs *d*. By depressing the cover 90, the cover 77 is also depressed whilst the arm 92 is raised.

90 Between the studs *d* are arranged two rock shafts 91 and 93. The shaft 93 is provided with a pointed link secured on the C cover designated by the reference U whereas the shaft 91 is provided with the arm 95 and the pointed link 79 of the cover 96. A plate spring *r* located underneath the pointed link 79 depresses the cover 96 which closes the

hole B_b through which the sound B_b is emitted. A stronger spring s lifts the cover 90 by overcoming the action of the spring r of the cover 96 acting on the arms 95 and 92 and consequently depresses the arm 95 and lifts the cover 96 corresponding to the sound B_b. On said cover is welded a lug 97 under which is located the arm 98 of the ordinary B_b finger piece.

10 The acoustic range of the saxophone has been increased by adding top F_# operated by the left ring finger and top G operated by the right forefinger. To produce said notes, a rod 100 is rockingly carried between studs g. One end of said rod has welded thereto a finger piece 101. Its other end has secured thereto in opposite direction a cover 102 corresponding to top F_#. Another rod 103 rockingly carried between studs h is fitted at 15 one end with a finger piece 104 and at its other end and in the opposite direction with top G cover 105.

As illustrated in Figure 4, the mechanism for performing the automatic actuation of the octave keys by means of one finger piece only i. e. of one finger comprises the plate 30 on which the left ring finger can bear. This plate 30 is welded to a rod 31 on which are secured two levers 32 and 33 which are 25 respectively positioned underneath the levers 47 and 46. Between the studs n is carried a rock shaft divided into four parts 34, 35, 36, 37. On the part 34 is secured the arm 47 and the upper connection 38. On the part 35 are secured a lug 39, the lower connection 40 and the octave cover 41. On the part 35 is secured an arm 42 and a lug 43. Lastly on the part 37 are secured the arms 44 and 45 and an arcuate arm 45 which is positioned 40 under the ring on the mouth-piece holder 99. Underneath the rock shafts is placed a spring 40^a.

The lever 20^a of the rockingly supported finger piece 20 presses upon the arms 42 and 44 owing to a flat spring located underneath said finger piece (not shown). A spring j lifts the cover 41. Another spring k overcomes the action of the spring j and depresses the cover 41. A further spring l of greater 45 strength lifts the lever 45 and consequently the ring of the mouth-piece holder 99 and the octave finger piece of said holder. Therefore, by depressing the finger piece 20, the arms 44 and 45 are lifted as well as the octave finger piece of the mouth-piece holder. Furthermore by continuing to depress the finger piece 20, if the plate 30 that is lifted by a spring 50 is depressed, the arms 33 and 46 are also lifted whilst the members 45 and 99 are lowered. 55 Thus the arm of the mouth-piece holder is lowered and closes the octave keys. By the same operation, the arms 32 and 47 and the connection 38 are lifted. When thus lifted, the latter allows the spring j located under the 60 pointed link 41 to lift the latter.

It will be appreciated that without departing from the spirit of the invention as will be pointed out in the appended claims, numerous constructional changes might be introduced in the foregoing mechanisms which are only adapted to exemplify the way in which it is possible to open and close the sound-emitting holes in the proper sequence as postulated by the novel principles underlying the invention.

What I claim and desire to secure by Letters Patent is:—

1. A saxophone comprising a barrel sequentially pierced with holes spaced from one another to the musical extent of a half tone and mechanisms including a series of rock shafts mounted in bearing studs on the barrel and a set of covers and plates for the holes and finger pieces for the actuation of said covers and plates, said mechanisms being adapted for the production of an open lowest sound C_#.

2. A saxophone comprising a barrel sequentially pierced with holes spaced from one another to the musical extent of a half tone and mechanisms including a series of rock shafts mounted in bearing studs on the barrel and a set of covers and plates for the holes and finger pieces for the actuation of said covers and plates in the required sequence, said mechanisms being adapted for the production of an open sound E_b.

3. A saxophone comprising a barrel sequentially pierced with holes spaced from one another to the musical extent of a half tone and mechanisms including a series of rock shafts mounted in bearing studs on the barrel and a set of covers and plates for the holes and finger pieces for actuating said covers and plates in the required sequences, said mechanisms being adapted for the production of the sequence of whole tones F_#, G_#, A_# and C by lifting one finger only for each tone, and moreover comprising eleven rock shafts connected to the respective covers adapted to close the corresponding holes in the required succession.

4. A saxophone comprising a barrel sequentially pierced with holes spaced from one another to the musical extent of a half tone and mechanisms including a series of rock shafts mounted in bearing studs on the barrel and a set of covers and plates for the holes and finger pieces for the actuation of said covers and plates in the required sequence, said mechanisms being adapted for increasing the acoustic range of the saxophone by the addition of a high F_# operated by the left ring finger and a high G operated by the right forefinger.

In testimony whereof I affix my signature.
LEON LEBLANC.
